UNITED STATES PATENT OFFICE.

AARON H. HOWARD, OF SALINE, MICHIGAN.

TOMBSTONE OR MONUMENT.

No. 833,212.

Specification of Letters Patent.

Patented Oct. 16, 1906.

Application filed April 30, 1906. Serial No. 314,540.

To all whom it may concern:

Be it known that I, AARON H. HOWARD, a citizen of the United States, residing at Saline, in the county of Washtenaw and State of Michigan, have invented a new and useful Tombstone or Monument, of which the following is a specification.

This invention relates to tombstones or monuments, and has for its object to provide a comparatively simple, inexpensive, and efficient device of this character for marking or identifying graves.

A further object of the invention is to provide a supporting-base having a pocket or recess formed therein for the reception of an inscription-plate or tablet, whereby the inscriptions on headstones and similar identifying devices which have become worn, cracked, or otherwise injured by exposure to the elements may be conveniently mounted or housed so as to preserve the inscription and give the same a neat attractive appearance.

A still further object is to provide an inscription-pocket one wall of which is formed with an angularly-disposed shoulder or lip for engagement with the adjacent end of the inscription-plate, while the base or rear wall of the pocket is disposed at an angle to the longitudinal axis of the tombstone, whereby the plate may be supported in an inclined position, so as to effectually display the inscription thereon.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a part of this specification, Figure 1 is a perspective view of a tombstone or monument constructed in accordance with my invention.

Fig. 2 is a similar view with the inscription-plate detached.

Similar numerals of reference indicate corresponding parts in both figures of the drawings.

The device consists of a supporting-base 5, upon which is mounted in any suitable manner the tombstone or body portion 6, the latter being substantially triangular in shape, as shown, and formed of stone, concrete, cement, or other suitable material. The body por-

tion 6 is formed with an inclined lip or shoulder 7, defining a pocket for the reception of an inscription-plate 8, the rear wall of the pocket being formed by the inclined face 9 of the body portion 6, so that the plate will be disposed at an angle to the vertical axis of the body portion 6 and in position to effectually display the inscription thereon. The inscription-pocket preferably extends the entire width of the body portion 6, while one end of the inscription-plate 8 is inclined or beveled, as indicated at 10, so that when the plate is mounted on the body portion the inclined end 10 thereof will be disposed in alignment with the rear vertical wall of said body portion.

By having the body portion 6 formed with the plate-receiving pocket the inscriptions on tombstones and other identifying devices that have become cracked, broken, or otherwise injured by continuous exposure to the elements may be conveniently mounted or housed so as to preserve the same. If desired, however, the inscription-plates or tablets may be manufactured separately and the desired inscription cut or otherwise carved in the face thereof and said tablets placed in position on the tombstones or monuments when desired. It will also be understood that the body portion 6 instead of being made of cement or other plastic material may be formed of stone, and that the inscription tablet or plate may be made of metal, granite, or other suitable material capable of effectually withstanding the action of the elements.

Attention is called to the fact that the inclined lip or shoulder serves to prevent accidental displacement of the tablet or inscription-plate, while the inclined face of the pocket not only serves to support said plate at the desired angle or inclination, but also presents an extended bearing-surface for the reception of cement and other adhesive material used in securing the plate to the tombstone or monument.

From the foregoing description it will be seen that there is provided an extremely simple and inexpensive device admirably adapted for the attainment of the ends in view.

Having thus described the invention, what is claimed is—

1. A tombstone comprising a body portion having an angularly-disposed stop-shoulder defining a pocket for the reception of an inscription-plate, and an inscription-plate seat-

ed within the pocket and having one end thereof bearing against the stop-shoulder and its opposite end disposed in alinement with the rear vertical wall of said body portion.

2. A tombstone comprising a base, a triangularly-shaped body portion mounted on the base and provided at its forward end with an inclined stop-shoulder defining a pocket for the reception of an inscription-plate, the rear wall of said pocket being inclined or beveled and formed by the adjacent face of said body portion, and an inscription-plate seated in

the pocket and having one end thereof bearing against the shoulder and its opposite end 15 inclined or beveled and disposed in vertical alinement with the rear wall of the body portion.

In testimony that I claim the foregoing as my own I have hereto affixed my signature 20 in the presence of two witnesses.

AARON H. HOWARD.
